UNITED STATES PATENT OFFICE.

ROBERT B. GRIFFIN, OF NEW YORK, N. Y.

DESIGN FOR A WALL-COVERING.

44,002.

Specification for Design.

Patented May 13, 1913

Application filed November 23, 1911. Serial No. 662,061. Term of patent 3½ years.

To all whom it may concern:

Be it known that I, ROBERT B. GRIFFIN, a citizen of the United States, and a resident of the borough of Manhattan, city and State of New York, have invented a new, original, and ornamental Design for a Wall-Covering, of which the following is a description.

The design is shown in the accompanying drawings.

That end of the wall covering marked 11 in Figure 1^a, joins onto the end marked 10 in Fig. 1, and the end marked 12 in Fig. 1^a, joins onto the end marked 13 in Fig. 1^b. The end marked 14 of Fig. 1^b joins onto the end marked 15 in Fig. 1^c. The four views when joined as stated make one repeat.

On the body A, of the wall covering is represented a series of pictures of children

in different poses. One of the edges of the wall covering is provided with the ornamental border B. The background, the different figures or pictures and the ornamental border may be colored or tinted as desired.

The design is adapted for the upper border of a wall covering and especially for nurseries or children's playrooms.

I claim:

The ornamental design for wall covering as shown and described.

In testimony that I claim the foregoing as my own, I have hereto affixed my signature in the presence of two witnesses.

ROBERT B. GRIFFIN.

Witnesses:

FRANK H. GRIFFIN,
JOHN J. RANAGAN.

Copies of this patent may be obtained for five cents each, by addressing the "Commissioner of Patents, Washington, D. C."
